LIGHT MACHINE GUN.

Application filed January 27, 1925. Serial No. 5,130.

To all whom it may concern:

Be it known that I, BEDŘICH SCHREIBER, a citizen of Czechoslovakia, residing at Prague, Czechoslovakia, have invented certain new and useful Improvements in Light Machine Guns, of which the following is a specification.

This invention relates to light machine guns of the kind in which no provision is made for water cooling and consists in an arrangement which enables the hot barrel to be readily exchanged by four manipulations and without changing the position of the gun.

15 In the accompanying drawings,

Fig. 1 is a side elevation, partly in longitudinal section, of a machine gun embodying the invention,

20 Figs. 2 and 3 are cross sections on line I—I of Fig. 1 illustrative of certain parts in two different positions.

Fig. 4 is a partly sectional elevation of the gun barrel and piston cylinder.

25 Fig. 5 is a section on line III—III of Fig. 4 and

Fig. 6 is a section on line IV—IV of Fig. 4.

Fig. 7 is a rear elevation of the barrel head.

30 Fig. 8 is a detail showing the locking device.

Fig. 9 is a side elevation of the gun casing and

Fig. 10 is a front elevation thereof.

35 The machine gun comprises four main parts, namely:

1. The gun barrel A with its accessories 1, 2, 3, 4, 5.

40 2. The gun casing B, containing the gun lock and feed device and having at its front face a hook-shaped extension 6 and a locking pawl 7.

45 3. The piston cylinder C for the operating piston 14. This piston cylinder extends with its forward end 9 into a bore 11 of the barrel-head 2 (Fig. 7), while its rear end is provided with a segmental flange 8 which engages a slit formed by the hook-shaped extension 6 of the gun casing B. The piston cylinder C also carries a saddle 10 for the support of the gun barrel A.

50 4. A pair of folding legs D suitably connected to the piston cylinder.

In action the bullet on leaving the barrel 55 passes through the barrel head 2 and the silencer 3.

The gases issuing from the barrel immediately behind the bullet are trapped in the barrel head 2 and their pressure actuates the piston 14 against the spring by which it is supported. This backward movement of the piston 14 actuates in known manner the devices housed in the gun casing B whereupon the spring is released and the piston 65 resumes its initial position, ready to repeat the operation.

The barrel A is secured by means of a segmental or interrupted screw thread 1 in a correspondingly interrupted female thread 70 in the bore of the gun casing B.

In order to enable the barrel when hot to be grasped by the hand for the purpose of exchange, it is provided with a handle 5 of heat insulating material. This handle 75 in order to avoid obstructing the sights when taking aim, is adapted to be turned around on the barrel through an angle of approximately 90°.

The barrel head 2, the silencer 3, and the sight 4 are rigidly secured to the barrel A, while the piston cylinder fits slidably into the barrel head 2.

80 When it is desired to exchange the barrel A together with its accessories (Fig. 1) the locking pawl 7 is released and the gun casing swung as in Fig. 2 the respective positions before and after such operation being illustrated in Figs. 2 and 3.

85 This movement has caused the interrupted screw threads 1 of the barrel A to be released so that the barrel can now be completely withdrawn, by being shifted axially forward by means of the handle 5, and be 90 left to cool.

95 The cold reserve barrel is placed on the saddle 10 and inserted into the gun casing B until stopped by its collar 16, when the casing is swung back to former position. The locking pawl 7 reengages automatically and the machine gun is restored to its original position (Fig. 1) so that after turning the barrel handle 5 down, firing can be continued.

100 105 The exchange of the barrels can thus, according to this invention be effected in a most simple and quick manner, by the per-

formance of a few manipulations, without the assistance of any tools whatever and without in the slightest degree disturbing the direction of fire to which the gun has been set.

The piston cylinder C is provided parallel to its axis with a rib 15 adapted to register with and engage a groove cut into the collar 16 of the barrel so as to facilitate the 10 positioning of the barrel in the gun casing.

The barrel head 2 is rigidly secured to the barrel while the hollow adjusting nipple 13, serves on the one hand to secure the silencer and on the other hand to allow the 15 bullet to pass through.

For firing blank cartridges, the silencer 3 is removed and the adjusting nipple 13 is replaced by a nipple having a restricted bore, so that the paper wad is forcibly 20 passed through the said bore and sufficient gas pressure is created in the barrel head 2 to actuate the piston.

After a great number of shots has been fired, powder residue accumulates in the 25 barrel head. In order to enable this to be cleaned out from time to time, a perforation 12 is provided which during firing is closed by the shovel-shaped end 9 of the piston cylinder Fig. 4 so as to prevent leakage of 30 gases. When the barrel is removed the perforation 12 is uncovered and thus accessible.

The oscillatory displacement and maintenance of the gun casing B is determined on 35 the one hand by the pawl 7 co-operating with the notch 17 and on the other hand by the pin 19 in co-operation with the notch 18, Figs. 2, 3, 5. The rear end 8 of the piston cylinder C embraces the cylindrical boss 40 22 of the casing B, Figs. 1, 9, while the lower part formed by the segmental flange at the said end 8 engages the segmental groove 21, Figs. 9, 10.

Fig. 8 shows the action of the pawl 7 45 which under the pressure of the spring-actuated bolt 20 is constrained to automatically enter into holding engagement when the casing is brought back into its original position.

Having now particularly described and ascertained the nature of my said invention and in what manner the same is to be performed, I declare that what I claim is:—

1. A machine gun of the type having no 55 provision for water cooling, comprising, a gun casing, a barrel connected to the gun casing by segmental screw threads which interengage by relative rotary movement of the barrel and casing through an angle 60 of less than 90°, and an axial rib and groove

interengageable to permit axial but prevent rotary movement of the barrel.

2. A machine gun according to claim 1, said barrel being provided at its rear end and directly in front of its segmental screw 65 threads with a collar, a piston cylinder co-operating with the casing, the collar carrying said axial groove, said axial rib being formed on the piston cylinder.

3. A machine gun according to claim 1, 70 and a handle of heat resisting material mounted rotatably and non-slidably on said barrel.

4. A machine gun of the type having no provision for water cooling, comprising, a 75 gun casing, a barrel connected to the gun casing by segmental screw threads which interengage by relative rotary movement of the barrel and casing through an angle of less than 90°, and an axial rib and groove 80 interengageable to permit axial but prevent rotary movement of the barrel, said barrel being provided at its rear end and directly in front of its segmental screw 85 threads with a collar, a piston cylinder co-operating with the casing, the collar carrying said axial groove, said axial rib being formed on the piston cylinder, and a handle of heat resisting material mounted rotatably and non-slidably on said barrel. 90

5. A machine gun according to claim 1, and a piston cylinder in combination therewith for actuating firing and repeating mechanism in said gun casing, under the influence of the gases issuing from the barrel mount, said piston cylinder comprising a semi-cylindrical shovel shaped extension formed at its front end and positioned in proximity to the barrel mouth, an annulus in a segmental flange integrally formed at 95 the rear end of the cylinder and positionable concentrically with the barrel bore, said axial rib and groove being respectively on the cylinder and barrel, and a flexible pedestal secured to the underside of the cylinder. 100

6. A machine gun according to claim 1, said casing having a hollow projecting boss on its front face, a piston cylinder, an annulus carried by the piston cylinder and rotatably receiving the boss, and a locking means to maintain the casing in its end position during and after exchange of a barrel. 110

In testimony whereof I have signed my name to this specification.

BEDŘICH SCHREIBER.
